UNITED STATES PATENT OFFICE

148,674

DESIGN FOR A BOOK COVER

Philip M. Brown, Elmhurst, Ill.

Application June 25, 1946, Serial No. 131,001

Term of patent 14 years

(CL. D6—2)

To all whom it may concern:

Be it known that I, Philip M. Brown, a citizen of the United States, residing at Elmhurst, in the county of Du Page and State of Illinois, have invented a new, original and ornamental Design for Book Covers, of which the following is a specification, reference being had to the accompanying drawing, forming part thereof.

Fig. 1 is a top plan view of a book cover showing my new design; and

Fig. 2 is a bottom edge view, partly broken away, for convenience of illustration.

The back of the book cover is conventionally plain.

I claim:

The ornamental design for a book cover, as shown and described.

PHILIP M. BROWN.
